UNITED STATES PATENT OFFICE.

ISAAC V. MORRELL, OF ELGIN, ILLINOIS.

VOICE INTENSIFIER.

1,415,462.

Specification of Letters Patent.

Patented May 9, 1922.

Application filed January 20, 1921. Serial No. 438,742.

To all whom it may concern:

Be it known that I, ISAAC V. MORRELL, a citizen of the United States, residing at Elgin, in the county of Kane and State of

5 Illinois, have invented certain new and useful Improvements in Voice Intensifiers; and I do declare the following to be a full, clear, and exact description of the invention, such as will enable others skilled in the art to 10 which it appertains to make and use the same.

This invention relates to an improved voice intensifier for use by singers and preachers and one object of the invention 15 is to provide a voice intensifier so constructed that the mouth-piece thereof may enclose the mouth and chin and fit against the throat and lower portion of the face, a plate being mounted in the mouthpiece for 20 extending beneath the chin and directing the sound waves through the mouthpiece into the horn of the voice intensifier.

Another object of the invention is to so 25 construct the voice directing plate that it may have movement with the chin.

Another object of the invention is to provide an improved reed carrier which may be 30 removably mounted in the mouthpiece adjacent its junction with the horn so that the sound waves will pass through the reed.

Another object of the invention is to so 35 construct this reed carrier that the voice directing plate may be carried by the reed carrier and removed from the mouthpiece with the voice directing plate.

Another object of the invention is to provide an improved type of horn, the horn being so constructed that the mouthpiece 40 will be prevented from being vibrated and the sound waves first caused to take a rotary movement and then to be vibrated horizontally.

Another object of the invention is to so 45 construct this intensifier that the sound waves may be controlled and thus a clear tone produced.

Another object of the invention is to so 50 construct this voice intensifier that all of the sound waves will be caused to pass through the mouthpiece and into the horn.

Another object of the invention is to provide an improved type of handle for the voice intensifier, the handle being so constructed that it may be swung from a posi-

tion at substantially right angles to the 55 mouthpiece to a folded position in which the handle will engage the horn of the voice intensifier.

Another object of the invention is to so 60 mount this handle that it may not be swung beyond a desired point and to provide an improved device for releasably holding the handle in an extended or operative position.

This invention is illustrated in the accompanying drawings, wherein:

Figure 1 is a side elevation showing the 65 voice intensifier in use.

Figure 2 is a perspective view looking toward the rear end of the voice intensifier.

Figure 3 is a view looking into the forward end of the horn.

Figure 4 is a vertical sectional view 70 through the voice intensifier.

Figure 5 is a horizontal sectional view 75 through the voice intensifier.

Figure 6 is a perspective view of the reed carrier.

This improved voice intensifier is provided with a mouthpiece 1 and a horn 2 and is further provided with a handle 3 which is 80 connected with a yoke 4, the arms of which are pivotally connected with the sides of the mouthpiece 1 as shown at 5 so that the handle may be swung from an operative position at right angles to the mouthpiece to 85 a folded or inoperative position in which the handle will extend longitudinally of the intensifier and engage the horn. Abutment pins 6 are carried by the walls of the mouthpiece to limit the swing of the yoke when 90 the handle is moved to the operative position and a hook 7 which is formed of resilient wire is carried by the handle and adapted to engage the lower wall of the mouthpiece and thus securely but releasably hold the handle 95 in the operative position.

This mouthpiece is provided with upper and lower walls 8 and 9 which have their free edge portions cut inwardly as shown so 100 that the mouth and chin may fit within the mouthpiece with the edge of the lower wall 9 engaging the throat of the user and the edge of the upper wall and the edges of the side walls engaging the upper lip and sides of the lower portions of the mouthpiece. It 105 will thus be seen that the lower portion of the face will be confined in the mouthpiece.

The horn 2 which extends from the rec-

2

tangular mouthpiece 1 is formed of any suitable material and is provided with a throat portion 10 which is rectangular in shape so that the sound waves caused by talking 5 or singing will be prevented from causing the mouthpiece to vibrate. The rectangular throat 10 merges into a bell-shaped outer end portion for the horn which is provided with an inner portion which is circular in 10 cross section and an outer portion which is elliptical. By having the inner portion of the horn's outer section circular in cross section, the sound waves will be caused to move in a circular path after leaving the 15 rectangular throat portion of the horn. After leaving the circular portion 11 of the bell-shaped outer section of the horn, the sound waves will pass through the elliptical portion 12 of the horn and since the walls of 20 the horn have relatively thick upper and lower portions 13 which merge into relatively thin side portions 14, the sound waves will be caused to vibrate horizontally. Therefore, the construction of the horn will 25 serve to prevent vibration of the mouthpiece and will produce tones which will be very clear.

In order to increase the efficiency of the intensifier, there has been provided a reed 30 carrier 15 which is positioned in the mouthpiece adjacent the throat of the horn, the reed carrier being so positioned that the reeds 15' will extend vertically and at substantially right angles to the longitudinal 35 diameter of the intensifier. This reed carrier is in the form of a metal plate having side strips 16 which extend in flaring relation and upper and lower strips 17 and 18, the lower strip being bent to extend downwardly 40 and then bent to extend parallel to the upper strip. The strips or flanges which extend from the upper and lower and side edges of the reed carrying plate, will engage the walls of the mouthpiece, the flaring side 45 walls providing a good frictional binding which will serve to prevent the reed carrier from slipping out of place. In order to provide a very firm fastening for the reed carrier, but at the same time permit of the 50 reed carrier being easily removed, buttons 19 will be carried by the side walls of the mouthpiece for fitting into sockets 20 formed by pressing the side strips. Openings are formed in the reed carrying plate above and 55 below the central cutout thereof and a length of cat-gut or other suitable material which forms the reeds 15' will be threaded through the openings. The reed carrier is made removable so that a reed carrier provided 60 with reeds of a certain size may be removed and a reed carrier having reeds of a different size put in place. In the preferred form, one of the reed carriers will have reeds formed from a number 1 banjo string, 65 the openings being so positioned that the

reeds or strings will be provided to the number of 32 to an inch. In the second reed carrier, a number 2 banjo string will be made use of and the reeds will be provided to the number 25 to an inch. In the next 70 reed carrier, number 3 banjo strings will be used and sixteen reeds to the inch will be provided. It will thus be seen that the different reed carriers may be removed and the proper reed carrier put in place, the reed 75 carrier having the finer reeds being used for a soprano or tenor voice, the second reed carrier having the medium reeds being used for a contralto or baritone voice and the reed carrier having the coarser reeds being 80 used for a base voice. When this intensifier is in use, the voice should be directed through the mouthpiece and reeds into the horn and in order to do so there has been provided a voice guiding plate 21 which is formed of 85 thin resilient metal. This plate is riveted to the lower strip or flange 18 and extends towards the open end of the mouthpiece and has its free end portion cut inwardly as shown at 22 so that the thin plate may 90 extend beneath and engage the chin of the user without causing any discomfort. By having this plate formed of thin resilient metal, it will remain in engagement with the chin and will move with the chin thus at 95 all times providing a voice guiding plate which will be in the proper position to hold the sound waves in the upper portion of the mouthpiece and direct the sound waves through the reed carrier into the horn. 100

When this device is in use, the handle is swung to the operative position and the lower wall of the mouthpiece will be engaged by the hooks 7. The intensifier will then be held by this handle and the lower portion of the face placed in the mouthpiece with the chin resting upon the voice guiding plate 21. When it is no longer desired to use the intensifier, the hook 7 will be released and the handle can be swung forwardly so 105 that it will extend longitudinally of the intensifier with the free end of the handle engaging the horn. If another speaker or singer is to use the intensifier, and has a higher or lower voice than the previous 110 user, it is simply necessary to remove the reed carrier together with the chin engaging plate and insert the proper reed carrier. As previously explained, the construction 115 of the horn prevents the mouthpiece from being vibrated by the sound waves passing through the rectangular throat and the sound waves are then caused to take a rotary movement as they pass through the circular portion of the horn and are then curved to 120 vibrate horizontally as they pass through the elliptical outer end portion of the horn, thereby producing a very clear tone. An intensifier has thus been provided which will 125 be very effective in operation and which will 130

be so constructed that it may accommodate itself to the voice of the speaker or singer.

I claim:

1. A voice intensifier comprising a horn and a mouthpiece for engaging the face and throat of the user, and a flexible plate in said mouthpiece for extending beneath and engaging the chin of the user and directing the voice through the mouthpiece into the 10 horn.

2. A voice intensifier comprising a horn and a mouthpiece for engaging the throat and enclosing and engaging the lower portion of the face of the user, and flexible 15 means within said mouthpiece for extending beneath the chin of the user and directing the voice through the mouthpiece into the horn.

3. The structure of claim 2 having the 20 voice directing means as an element removable from the body of the mouth-piece and positioned for engaging the chin and moving vertically with the chin when in place.

4. A voice intensifier comprising a horn 25 and a mouth-piece, a flexible plate in the mouth-piece for extending beneath and engaging the chin of the user and directing the voice through the mouth-piece, and means for mounting the flexible plate within the 30 mouth-piece consisting of an open frame fitting within the mouth-piece and having the plate connected therewith.

5. The structure of claim 4 having the 35 mounting frame for the flexible plate in the form of a plate having its intermediate portion open and having its edge portions provided with tongue extensions for engaging the walls of the mouth-piece to hold the

frame in place within the mouth-piece, the chin-engaging plate being secured to one of 40 said tongues.

6. A voice intensifier comprising a horn, and a mouth-piece, a plate in the mouth-piece having its intermediate portion open and having its upper, lower and side edge 45 portions provided with resilient tongue extensions engaging the mouth-piece to frictionally hold the plate in place, and a flexible plate carried by and extending from the lower tongue extension longitudinally of the 50 mouth-piece for engaging the chin of the user and moving with the chin to direct sound waves through the mouth-piece and open frame into the horn.

7. A voice intensifier comprising a horn 55 and a mouth-piece, an open reed carrying frame in said mouth-piece and having wings extending from its edge portions for engaging the walls of the mouth-piece to releasably hold the frame in place, and a flexible plate 60 carried by and extending from the frame longitudinally within the mouth-piece for engaging the chin of the user and directing sound waves through the mouth-piece and frame. 65

8. A voice intensifier comprising a horn and a mouth-piece, an open reed carrier fitting within said mouth-piece, and a flexible element carried by and extending from the frame longitudinally within the mouth-piece 70 for engaging the chin and moving with the same and directing sound waves through the mouth-piece and reed carrier.

In testimony whereof I have hereunto set my hand.

ISAAC V. MORRELL.
